UNITED STATES PATENT OFFICE

2,576,826

METHOD OF BINDING LAMINATED MATERIAL

Frank G. Dobbs and Stephan H. Dobbs,
New York, N. Y.

Application December 15, 1948, Serial No. 65,366

2 Claims. (Cl. 18—56)

1

The invention relates to the art of binding laminated material, and relates more particularly to the art of manufacturing receptacles of the type made of flexible thermoplastic laminated material.

Desirable features for wallets and similar receptacles and their manufacture include selection of a suitable material to provide durable protection for the bills and other articles deposited therein, and a minimum of operational steps in their assembly; and these features, generally speaking, may be found in most wallets and in their manufacture, as of present day use. However, most wallets, especially of the inexpensive type now in use are deficient in failing to provide for securing means that are resistant to protracted chemical influence, such as human perspiration, and mechanical influences, such as continued folding and unfolding. Furthermore, most wallets are constructed of a great amount of parts which makes for costly manufacture, due to the need for many dies and fixtures and the long time involved in the fabricating operations. Moreover, present wallets in most cases have not lent themselves well for production line manufacture.

An object of the invention is the provision of bonding of parts thereby obviating the use of separate securing means.

A further object of the invention is to provide a method of preparing a blank of plastic with straight impressions at predetermined locations under the influence of pressure and heat to form creases for subsequent folding.

Further objects and advantages of the invention will be set forth in part in the following specification and in part will be obvious therewithout being specifically referred to, the same being realized and attained as pointed out in the claims hereof.

With the above and other objects of the invention in view, the invention consists in the novel methods, as set forth in the claims hereof, certain embodiments of the same being illustrated in the accompanying drawings and described in the specification.

For a fuller understanding of the nature and objects of the invention reference should be had to the following detailed description, taken in connection with the accompanying drawings, in which:

Fig. 1 is an elevational view of a blank for a

2

receptacle in accordance with the invention, with a slide fastener sealed to the blank;

Fig. 2 is an elevational view of the blank of Fig. 1, folded once;

Fig. 3 is an elevational view of the completed receptacle;

Fig. 4 is a schematic view, showing an apparatus for use in creasing and heat-sealing in accordance with the invention; and

Fig. 5 is a fragmentary sectional view on an enlarged scale, taken along line 5—5 of Fig. 1, illustrating a crease impression.

As best shown in Fig. 1, the wallet is folded from a single blank 30 that preferably consists of a plastic material characterized therein that it is heat-sealable or bondable.

The blank 30 is subjected to an operation for providing a plurality of creases or impressions. For the purpose of clarity and simplicity these

impressions have been illustrated in Fig. 1 as single dot-and-dash-lines, although the impressions, as best visible in Fig. 5, have a groove-like appearance. This creasing is made on a conventional electronic heat-sealing apparatus. As

schematically illustrated in Fig. 4, the blank 30 is placed on a platen 31 of the apparatus, which platen is electrically interconnected to a generator 32 of high frequency current. A knife-like creasing tool 33 is disposed above said platen

31, and is connected to, and movable with a carrier (not shown), in opposite directions as indicated by an arrow 34. The carrier may be secured either to the piston of an hydraulic or an air cylinder, or to any other suitable reciprocable moving means. The tool 33 is either directly or

indirectly interconnected electrically to the generator to complete the electronic circuit.

In the schematic illustration the tool 33 has been shown but for a single crease line. Actually

40 all the crease lines of the blank are made at the same time, with the tool 33 having as many edges 36 as are crease lines and positioned to make impressions at predetermined locations of the blank. The edges 36 may be about $\frac{3}{16}$ in. wide, and all

45 the edges are substantially straight, and are flush with each other for enabling simultaneous impression of all crease lines.

When the carrier is lowered, all the edges will make contact with the surface of the blank 30.

50 The contact is made at a predetermined amount of pressure (for instance 100 lbs.) and simultaneously heat is generated as caused by the gen-

erator 32, resulting in impressions (generally indicated at 37 in Fig. 5), at said predetermined locations of the blank. These impressions or crease lines appear as notches or grooves in at least one surface of the blank, and it is believed that the material of the blank at these locations is being compressed resulting in decreased thickness at said locations. It has been found, in accordance with the invention, that these straight impressions facilitate bending or folding about the same. Where the material is folded about these crease lines while the same is still under the influence of the previously generated heat, the folds become sufficiently preshaped to tend thereafter towards folded positioning.

The blank 30, as shown in Fig. 1, has a central rectangular portion divided by a crease line 38 to provide two substantially equally sized portions, namely an outer wall portion 39 and an inner wall portion 19 for the container 12 of the wallet. An extension 41 forming part of the pocket 14 of the wallet, is at one end (the right end, Fig. 1) of the outer wall 39 and has an edge 42 substantially in alignment with the edge 43 of the outer wall portion 39. The extension 41 is divided from the outer wall 39 by a crease 44 and has a flap to form the inner wall 22 of the pocket 14. The flap 22 is divided from the extension 41 by a folding crease 46 and its outer edge 47 coincides with that of the extension 41. The width of the flap 22, however, is smaller than that of the extension 41 providing a space 51 between the inner edge 48 of the flap and the longitudinal edge 49 of the inner wall portion 19 located opposite thereto for a portion. Said space 51 provides clearance for easy folding of the extension 41 about the crease 44.

A second extension 52 is provided at the other (left, Fig. 1) end of the outer wall portion 39 and forms part of the pocket 13. This extension has an edge 53 which is also substantially in alignment with the edge 43 of the outer wall portion, and the extension 52 is divided from the outer wall portion 39 by a crease 54. The extension 52, similar to the extension 41, has a flap; that flap is designated 56 and is provided with an inner edge 57 that is separated from the oppositely disposed edge 58 of the inner wall 19 by a space 59 dimensioned similar to the space 51 mentioned before. The flap 56 is divided from the extension 52 by a folding crease 61.

Said flap 56, however, is larger than the flap 22, and has a portion corresponding in size to the flap 22, forming the inner wall 21 of the pocket 13, and a second narrower portion that forms the inner wall 24 of the stay 23. That portion 24 has a part 62 that forms the outer wall of the stay 23 and from which it is divided by a bending crease 63 and with which it has a common outer edge 64.

The part 62 is severed from the second extension 52 by a cut providing an outer edge 66 of the extension 52. The crease 63 is located midway between the edge 67 of the part 62 and the edge 68 of the portion 24 of the flap 56; likewise, the crease 61 is disposed midway between the edge 53 of the second extension 52 and the edge 69 of the portion 21 of the flap 56; similarly, the crease 46 is located medially between the edge 42 of the extension 41 and the edge 71 of the first flap 22; and, finally, the crease 38 constitutes a medial line between the edge 43 of the outer wall 39 and the edge 72 of the inner wall 19 of the bill container 12.

The crease 63 of the stay 23 is off-set from the

crease 61 of the pocket 13 as the stay is narrower than the pocket, as best shown in Fig. 3. Similarly, the creases 61 and 46 of the pockets, substantially in alignment with each other, are off-set from the crease 38 of the bill container 12, as they form the upper edge of the pockets that are disposed below the upper edge 38 of the container, as illustrated in Fig. 3.

After the first folding as illustrated in Fig. 2, the edges 67 and 68 will be adjacent each other, and similarly will be the edges 52 and 69, the edges 43 and 72, and the edges 42 and 71. As the last named three pairs of edges are in alignment, the edges 43 and 72 of the container 12 will be adjacent the edges 52 and 69 of one pocket, on one side, and adjacent the edges 42 and 71 of the other pocket on the other side, as illustrated in Fig. 3.

The blank is subsequently folded along the 20 medial creases resulting in an appearance illustrated in Fig. 2.

Then, the pockets are folded inwardly, towards the inner wall 19 until the open ends 16 and 17 having edges 47 and 66, respectively, face each 25 other across the gap 20. The stay 23 is inserted with the edge 64 into the pocket 14 through the open end 17 thereof.

Then, a single sealing operation joins, simultaneously, the pocket walls to each other, the 30 container walls to each other, as well as the pockets to the containers, along a sealing line 86 that is positioned near the flush lower edges of said parts.

It will be apparent to those skilled in the art 35 that the novel principles of the invention disclosed herein in connection with specific exemplifications thereof will suggest various other modifications and applications of the same. It is accordingly desired that in construing the 40 breadth of the appended claims they shall not be limited to the specific exemplifications of the invention described herein.

Having thus described the invention, what we 45 claim as new and desire to be secured by Letters Patent, is as follows:

1. In a method of creasing and folding a piece 50 of flexible plastic heat-sealable material, the steps comprising supporting one surface of said material on a flat backing, subjecting the opposite surface at a predetermined location to the impression of a thin straight edge while simultaneously heating with high frequency electric current directly said material along the line where contact is made with said straight edge to compress the material, and to make a groove in said 55 opposite surface, at said location, whereby said material is provided with a crease, and subsequently folding said material away from said crease along the same while still at elevated temperature so that the crease forms the outer bending edge.

2. In a method of folding a piece of normally 60 flat pliable thermoplastic material, the steps comprising, supporting one surface of said material 65 on a plane backing, subjecting the opposite surface at a predetermined location to the impression of a thin straight blade while applying heat at that location, to compress the material at said location to form a straight groove, and folding 70 said material away from the said groove, whereby said fold will outwardly expose the groove at the folding edge.

FRANK G. DOBBS.
